UNITED STATES PATENT OFFICE.

GILBERT C. COTTRELL, OF SIDNEY, NEW YORK, ASSIGNOR TO JULIUS KAYSER & CO., OF NEW YORK, N. Y., A CORPORATION OF NEW YORK.

NECKTIE.

Application filed April 23, 1925. Serial No. 25,194.

My invention relates to neckties and has for its object a construction of tie which at the same time reduces the cost of manufacture, and produces a more satisfactory article than the ties at present in use.

My invention consists in the construction, combination and arrangement of parts described and claimed herein, and illustrated in the accompanying drawings.

10 In these drawings which illustrate a preferred embodiment of my invention, and in which similar reference characters designate corresponding parts in all views,

Figure 1 is a view of a tie embodying the invention;

Fig. 2 shows the double fabric from which the tie is made;

Fig. 3 is a section taken approximately on the line 3—3 of Fig. 1; and,

20 Fig. 4 is a section taken approximately on the line 4—4 of Fig. 1.

The usual four-in-hand tie is made of silk or other suitable material upon a basis of a strip of coarser and stronger material which 25 serves as a lining or foundation for the silk by which it is encased; and ties of this construction have the disadvantage in the first place that the lining material sometimes is not as strong as it should be and it breaks 30 away, leaving the tie useless; and in the second place when the tie is tied, the lining and silk wrinkle, but the silk more readily resumes its shape, while the lining material retains the wrinkle, and the tie thus loses its 35 flatness and becomes ill-shapen and difficult to tie satisfactorily thereafter.

According to my invention, I first provide a lining material 1 and a silk or facing material 2 and paste these two together over 40 their entire area so that in handling they may be treated as, and for all practical purposes do in fact constitute, a single piece of material. From this double material I cut sufficient material according to pattern for a tie 3, and fold this material over with the silk 2 on the inside and the lining material 1 on the outside, lining up the edges 4 and stitching them together as shown. The sleeve thus formed, shaped according to the pattern used, which is open at the ends, is then turned inside out, bringing the silk 2 on the outside, and the lining material 1 on the inside, and concealing the seam or edges 4 where they were stitched, as shown in section 55 in Fig. 3.

The making of the tie is thus extremely simple, and the result is that we have a tie 3 in which the lining material and the silk or other covering forming the facing are cemented or pasted together throughout and 60 thus act in substantially the manner of a single piece of material, except that the lining is at all times joined with, and is practically integral with, the silk, so as to take the strain, whatever strain may be placed 65 upon the tie, thus enabling the tie to retain its shape indefinitely.

As a lining material 1 I prefer to use a warp-knitted fabric, which is a knitted fabric which is elastic or stretchable in one direction, but is substantially rigid in the other direction; and in cutting the ties from from this fabric it is desirable to cut them so that the direction of rigidity of the lining material is longitudinal, and that of elasticity 70 is lateral of the tie; and thus when the tie is used, the strain put upon it in drawing it through the collar when tying it comes in the direction in which the material does not yield. While the facing material or silk 75 may be of any suitable fabric, if a similar warp-knitted fabric is used, it is desirable that it be placed upon the lining fabric in exactly the same manner when they are being pasted together; that is to say, so that the 80 direction of elasticity is lateral, and the fabric has no give in the direction of the 85 length of the tie.

In order to finish the exposed edges at the edge of the tie and prevent unraveling of the 90 goods, it is desirable to bind these edges with tape 5. This is preferably done before the edges 4 of the tie are sewn together, so that the ends of the tape also are concealed within the tubular sleeve when it has been turned 95 right-side-out.

Having now described my invention, I claim and desire to secure by Letters Patent:

A necktie comprising a facing material and a lining material of warp-knitted fabric united thereto throughout their contacting surfaces, each arranged with its direction of greatest rigidity longitudinal of the tie.

In testimony whereof I have signed my 105 name to this specification.

GILBERT C. COTTRELL.
